UNITED STATES PATENT OFFICE.

HOWARD C. LISLE, OF LANSING, MICHIGAN, AND FRANK H. LEWIS, OF SAN JOSE, CALIFORNIA, ASSIGNORS TO BEAN SPRAY PUMP CO., OF SAN JOSE, CALIFORNIA, A CORPORATION OF CALIFORNIA.

ELEVATOR.

Application filed April 27, 1927. Serial No. 186,850.

Our invention relates to elevators of the fluid pressure operated type, in which the platform is mounted directly upon the movable member or plunger of the actuating mechanism.

In such devices, it is common practise to provide a fixed cylinder with a plunger operable therein, the upper end of said plunger extending through packing at the top of said cylinder and supporting the platform. When the plunger and platform are elevated, the polished surface of said plunger is exposed, and, being necessarily greasy, may collect a coating of sand or other foreign substances, which, upon the subsequent lowering of the plunger, cut and wear both the packing and the polished surface of the plunger.

Elevators of this character are commonly used to lift automobiles off the ground, to enable their running gear and under parts to be washed or otherwise worked upon, and in such washing it is almost impossible to prevent sand and dirt from being deposited upon the exposed polished surface of the plunger. In some cases solvents or caustic solutions are used in such washing, which have a deleterious action on the surface of the plunger.

The principal object of our invention is to provide an elevator of the described type in which the polished surface of the plunger, i. e. that surface which comes in contact with the packing, is protected from the deposition and wearing action of foreign matter, to the end that the effective life of both packing and plunger may be greatly prolonged.

A second object of the invention is to provide a construction which will permit the platform to be turned, horizontally, when elevated. A still further object is to provide for the ready removal of the entire mechanism from the foundation well in which it is placed.

Although our invention is particularly adapted for elevators used for lifting automobiles off the ground to render their under parts accessible, it will be apparent that it may be put to any other use for which its construction renders it advantageous. Moreover, it is to be understood that the construction, proportion, and arrangement of the several parts, as herein described and illus-

trated, may be varied, within the limits of the claims hereto appended, without departing from the spirit of the invention as set forth in said claims.

A preferred embodiment of our invention will now be described fully with reference to the accompanying drawings, wherein:—

Fig. 1 is a vertical section of our complete elevator.

Fig. 2 is a vertical sectional detail of a modified construction for permitting the turning of the platform while elevated.

In the drawings, the reference numeral 1 designates a concrete well extending downwardly from the ground or floor level 2, and forming the foundation for the device. A cylinder 3 of light sheet metal may be used as an inner form or lining for said concrete. 4 is a base plate secured within the bottom of the well 1. 5 is a tubular member provided with a foot 6 adapted to rest upon the base 4. We prefer to provide a suitable bearing between the tube 5 and the base 4, of such a nature as to permit said tube to turn. One form of such a bearing is shown in Fig. 1, the meeting faces of the foot 6 and the base 4 being conical and formed to fit accurately together, as shown at 7.

A second tube 8, which constitutes the reciprocating part or plunger of the device, surrounds the tube 5 in spaced relation. The upper end of said outer tube is closed, and is attached to the lifting platform, a portion of which is shown at 9. Between the inner and outer tubes are guide rings 10, secured to the inner tube, and upon which the outer tube slides. One such ring is positioned near the top of the inner tube, and another at a point somewhat above the upper limit of travel of the bottom of the outer tube. Suitable packing, preferably in the form of a cup leather 11, is positioned immediately above each guide ring.

The operating fluid is introduced and discharged through a pipe 12, provided with a suitable controlling valve indicated at 13. This pipe may be embedded in the concrete of the well 1, as shown, and is connected with a passage 14 formed in the base 4, and said passage registers with an aperture 15 in the foot 6, whereby the fluid may enter or leave the inner tube 5. It will be seen that introduction of fluid under suitable pressure into

the inner tube 5 will cause the outer tube 8 and the platform 9 to rise.

A suitable cover plate 16 is provided to exclude water and foreign matter from the well 1, and said plate also provides an annular guide at 17 for the upper end of the tubes, the outer tube being a free sliding fit therein. A light packing may be provided at 18, merely to protect the guide bearing 17.

10 The only polished surfaces are the inside of the outer tube 8 and the outside of the guide rings 10, and such surfaces, as well as the packing rings 11, are entirely protected. The bearing 17 is merely a guide, and is not 15 exposed to the fluid pressure. The outside of the tube 8, therefore, need not be polished. The bearing 17 is protected by the light packing 18, which can be easily renewed, but even if not so protected, the wear upon said 20 bearings caused by the intrusion of gritty matter from above is of small consequence.

The platform 9 can be easily turned, even when elevated, the inner tube 5 turning upon its bearing 7 in the base 4. If desired, a 25 bearing may be provided between the platform and the outer tube 8, instead of the bearing 7 at the base of the inner tube 5. Fig. 2 shows a preferred form of such bearing, 19 being a flanged cap secured upon the upper 30 end of the outer tube 8. The platform 9 is provided with a ball-race 20, and is rotatably held upon said cap 19 by an annular collar 21 also provided with a ball-race 21'. Bearing balls 22 in said races provide anti-friction 35 bearings between the platform 9 and the cap 19.

The entire device with the exception of the base 4 and the fluid supply pipe 12, is removable from the well 1, the foot 6 of the 40 inner tube 5 merely resting upon said base 4. The weight of the tubes and platform are

sufficient to prevent leakage of the fluid at the bearing 7.

We claim:

1. An elevator comprising a base; a longitudinally fixed inner member supported for rotation thereupon; a longitudinally movable tube surrounding said member and provided with a closed upper end; packing means between said member and said tube; and means for introducing fluid under pressure between the inner member and the closed upper end of said tube. 45

2. An elevator comprising a base having a fluid passage extending through it; a longitudinally fixed inner member rotatably supported upon said base and provided with a fluid passage communicating with the passage in said base; a longitudinally movable tube surrounding said member and provided 50 with a closed upper end; packing means between said inner member and said tube; and means for introducing fluid under pressure into said tube through the passages of the base and the inner member. 55

3. An elevator comprising a permanent receptacle forming a well; a base in said well having a fluid passage extending through it; a longitudinally fixed inner member and an outer tube longitudinally movable relatively 70 to said inner member, and forming a fluid receiving chamber between them, said inner member being rotatably supported upon said base and having a fluid passage connecting said chamber with the passage of said base; and means for supplying fluid to the passage of said base. 75

In testimony whereof we have signed our names to this specification.

HOWARD C. LISLE.
FRANK H. LEWIS.
